UNITED STATES PATENT OFFICE.

RUEL E. MOHNKERN, OF OIL CITY, PENNSYLVANIA.

ELEVATOR OF THE RIGID-YOKE TYPE.

Application filed May 24, 1923. Serial No. 641,099.

To all whom it may concern:

Be it known that I, RUEL E. MOHNKERN, a citizen of the United States, residing at Oil City, in the county of Venango and 5 State of Pennsylvania, have invented certain new and useful Improvements in Elevators of the Rigid-Yoke Type, of which the following is a specification.

The object, construction and utility of my 10 improved elevator are herein set forth with sufficient clearness to enable others skilled in the arts to which its construction and use respectively relate, to make and use the same.

15 The object of this invention is, to provide an elevator for pipe and other tubular elements of like nature, which is simple in construction and operation and which may be cheaply manufactured by reason of the 20 small amount of machine work and other labor required in its construction.

An additional object is, to provide an 25 efficient, safe, strong and easily operated elevator for use especially in connection with the tubular equipment of oil wells.

The construction of my improved elevator is clearly shown in the accompanying drawings in which:

Fig. 1 is a front elevation of my improved 30 elevator, showing a short section of tubing having a coupling or collar in position thereon, the latch-levers being shown in the tubing-retaining position.

Fig. 2 is a plan view, somewhat enlarged 35 as compared with Fig. 1, and showing both latch-levers in their inoperative, or tubing-releasing position.

Fig. 3 is a plan view of my improved 40 elevator showing the tubing in position therein with the latch-levers in the tubing-retaining position.

Fig. 4 is a vertical section of one side of the elevator on line IV of Fig. 3.

Fig. 5 is a plan view of one of the latch-levers employed in my improved elevator.

My improved elevator belongs to the 45 class known as solid-yoke, collar-engaging, double-bail elevators and is so constructed that its collar-engaging feature serves to lift and sustain the weight of the engaged 50 tubular element and also to maintain the interengaging of said yoke and said element when said element is being hoisted, or carried in a vertical position, or an approximately vertical position. At times, however, especially in the operation of pulling the tubular equipment of a well, the tubing

or casing, as the case may be, is not in a vertical position and may deviate therefrom at any angle to that of the horizontal, as hereinafter described, and at the time of such deviation it might be possible for the elevator to move longitudinally of the tubing sufficiently for the collar to be withdrawn from the engaging feature of the yoke. It is, therefore, necessary to provide some means which will, in case of such disengagement, still retain the yoke of the elevator in its service relation to and in engagement with its load, and for this purpose elements termed latch-levers are provided.

The construction of my improved elevator, thus broadly outlined, and clearly illustrated in the accompanying drawings is substantially as follows:

The body or main member 1 of my improved elevator, which is termed the yoke, is of U-shaped conformation, the gap or opening of which is formed by walls consisting of a rear, semi-circular portion 2 and continuing from each side thereof is a straight, parallel side portion 3, 3. The center radius r' for said semi-circular portion 2 is in the "center line" of said Fig. 2, and the inner opposing faces of said walls 3 extend at a right angle to said center line.

The width of the gap thus formed is slightly greater than the outside diameter of the tubular element upon which the elevator is designed to operate, said tubular being shown in transverse section in Fig. 3, also in elevation in Fig. 1 and is indicated by the reference numeral 4.

For the purpose of reception, engagement, lateral retention and support of a collar 5, which is employed for securing adjacent sections of said tubular elements together, and whereby said tubing is hoisted by means of my elevator, I form in the upper face of said yoke a partially walled socket, the side or vertical walls 6 of which are circular and have the radius r'' and are concentric with but of greater diameter than the portion 2 of the wall of said gap; said walls 6 are straight, vertical walls arranged in parallel relation to the axis of the yoke and the rear portion of said gap, and, as shown in Fig. 1, said socket has a considerable depth equal to approximately one-third the length of said collar 5; the extent of said circular wall 6 is approximately two-thirds of a circle and the diameter of the partial socket formed thereby is slightly greater than the outside diameter of said collar 5.

The annular projection 7 forming the bottom wall of said socket provides a shoulder for the engagement and support of the lower end face of the collar or coupling 5 to lift the element 4, and when said yoke engages said tubular element 4 and its collar 5 as shown in Fig. 1, said yoke and said tubular element cannot be disengaged through any relatively lateral movement of either of said structures. For the purpose of retaining said elements in engagement when their relative positions are other than that shown in Fig. 1, that is to say, when collar 5 is above said socket, latch-levers, to be later described, are employed.

Said yoke 1 is provided, upon each side thereof with a bail-lug 8, for the respective attachment of a bail 9, 9, for the engagement of a hoisting cable. Such bails are common to various types of elevators, are familiar to those skilled in the art, and need not be described in detail.

Said latch levers 10 perform two functions; firstly, that of insuring the axial alignment of the tubular element and the yoke respectively so that said collar 5 will readily enter its engaging socket; secondly, to prevent the disassociation or disengagement of said tubular element and said yoke when said collar is not engaged by said engaging feature.

This last function is necessary for the reason that, at times, when tubular equipment is being handled, especially when it is being pulled from or replaced within a well, it is in a horizontal position, and in such a case should the gap of the yoke face downwardly, disengagement of the elevator might occur if said yoke were not supplied with means other than said collar engaging feature or socket.

In order that said latch levers 10 may present no material obstruction or resistance to the entrance of the tubular element into the gap of the yoke, and for the purpose of adapting to automatically engage said tubular element, they are mounted and equipped as shown especially in Fig. 4, as follows:

The outer end of each side of said yoke, which extends parallel with the axis thereof, is formed into a housing for the respective latch lever 10 and a rotative hinge-pin 11 therefor, which pin also extends parallel to said axis. Each latch is adapted to swing in a horizontal plane perpendicularly or at a right angle to said axis and is rigidly secured to its respective pin 11 by means of a set screw 12. Surrounding the upper end of said pin 11 is a spring chamber 13 for the reception of a torsion spring 14, through which spring, said pin extends; one end of said spring is connected in any suitable way to said pin 11, and the other end thereof to

said yoke. Said spring is caused to be normally in torsional tension so that the recoil thereof actuates said pin rotatively, and the thereto attached latch levers into the respective positions shown in Fig. 3 so that the inner ends of said levers are positioned within the gap of the yoke and are yieldably, spring retained in this position. When a tubular element 4 is entered into the gap of said yoke, the inner ends of said levers will be thereby actuated laterally out of said gap and when said tubular element is in the hoisting position shown in Fig. 3 said latches will be automatically spring-actuated to their retaining position,—that is, with their inner extremities in juxtaposition to the periphery of said tubular element (see Fig. 80 3), so that the elevator is retained in proper service relation thereto, and accidental disengagement therefrom is thereby prevented.

When the elevator is to be disengaged or removed from said tubular element, the outer ends of the levers each of which is formed into a manipulating member 10' are manually actuated so as to swing them to their releasing position as shown in Fig. 2.

The degree of tension and recoil of said torsion spring 14 may be readily regulated by loosening the set screw 12 and turning pin 11 in the desired direction, then again tightening said screw.

I claim the following:

An elevator of the rigid yoke type adapted for use with a tubular element having a coupling collar secured thereto, comprising in combination a rigid yoke having a gap for the reception of said tubular element also a feature consisting of a straight-walled, concentrically-arranged enlargement of the upper rearward portion of said gap, the junctional point of the walls of said enlargement with the walls of said gap forming a square shoulder for contact with the lower end of said collar, the walls of said enlargement being of sufficient extent to engage said collar throughout more than one half of its circumference for the purpose set forth, latch-levers pivotally mounted within said yoke at each side of and adjacent the entrance of said gap so as to be moveable in a plane transversely to the axis of said yoke, a torsion spring arranged to actuate said levers to the position whereat their inner ends are within said gap with their inner faces in retaining juxtaposition to the periphery of said tubular element, said levers being manually actuatable to withdraw said ends from said gap, and bales carried by said yoke for the attachment of a hoisting cable.

In testimony whereof I affix my signature.
RUEL E. MOHNKERN.
